DIE

Francis J. Dedrick, Red Lion, Pa.

Application April 22, 1939, Serial No. 269,366

5 Claims. (Cl. 164—29)

This invention relates to cutting dies for use in a clicking press for dieing out blanks from sheet material such as upper leather for boots and shoes.

5 An object of the present invention is to provide an improved die in the nature of a closed frame formed from a strip of steel bent into curves and angles of the desired contour, an edge of the frame being beveled on both sides 10 to form a cutting edge, and in which a single channel is formed longitudinally in the exterior side wall of the frame, the channel being disposed intermediate the opposite longitudinal edges of the frame and having a convex surface, 15 the radius of which is approximately twice the maximum thickness of the wall of the frame.

Another object of the invention is to provide an improved clicker die which is more easily straightened and in which the possibility of fatigue cracks is greatly reduced.

Another object of the invention is to provide a stock for use in making clicker dies and comprising a cold drawn steel strip possessing the necessary qualities and characteristics and essentially preshaped with three angularly disposed flat sections which are at the inside of the die when the die is formed and having three arcuate sections on the outside wall, the intermediate arcuate section being convex and the other two 25 arcuate sections being concave with respect to the body of the die, so as to provide, with the angularly disposed inner wall sections, beveled surfaces along the top and bottom of the die.

With the foregoing and other objects and advantages in view, the invention consists in the preferred construction and arrangement of the several parts which will be hereinafter fully described and claimed.

In the accompanying drawing:

40 Figure 1 is a perspective view of one type of doubled edged clicker die constructed according to the present invention;

Fig. 2 is a vertical transverse section taken on the line 2—2 of Fig. 1; and

45 Fig. 3 is a view similar to Fig. 2 of a single edged clicker die.

The clicker dies heretofore constructed have had their cutting edges extending from a relatively heavy body portion. By such construction the dies are very difficult to handle, as they taper off from the heavy body to the cutting edge in such a manner that there is no surface by which the dies can be firmly gripped and held by an operator. Also these dies frequently crack in the

region of the heavy body portion, due to the development of fatigue cracks.

In order to overcome the above defects, considerable experimental work has been done on improving the construction of clicker dies. Since 5 these dies are a relatively cheap article of commerce and are used in large quantities, they require attributes to assure satisfactory work and an economical life.

Furthermore clicker dies have a recognized 10 field for cutting out materials to a definite pattern. Therefore, the dies must be constructed of suitable material having characteristics by which the dies can be properly shaped. The material used in constructing clicker dies should be 15 of small size and yet its outline must be of such accuracy that the handling must not deform the cutting edges or the pattern outline.

In order to produce clicker dies according to the present invention, it was first necessary to 20 produce suitable material from which the dies could be formed. Preferably the material used in constructing the clicker dies of the present invention is cold drawn steel which is rolled in strips so as to provide a die stock having definite 25 characteristics, as will be hereinafter more fully described.

Referring to the drawing, the clicker die 11 comprises a closed frame which, as is well known, may be of varying outline in accordance with 30 the particular shoe pattern to be cut. Such dies are commonly made of a single piece of die stock, cut to the proper length, bent into curves and angles of the desired contour, such as shown in Fig. 1, and having its ends connected by 35 welding.

A die, in accordance with the present invention, may be either single or double edged.

In order to construct the clicker dies so that such dies will have certain characteristics by 40 which the defects of the earlier types of clicker dies are overcome, it has been necessary to produce the dies from stock designed with a definite form.

Thus, in the case of a double edged die, the 45 stock preferably has the cross section shown in Fig. 2, while in the case of a single edge die the stock preferably has the cross section shown in Fig. 3.

Referring to Fig. 2, the side of the stock used 50 in forming the die 11, on the side constituting the inside of the frame, is formed with three angularly disposed flat sections, the intermediate section 12 being substantially vertically disposed and the other two sections 13, 14, being disposed 55

at an angle to said vertical section 12 and being inclined outwardly towards the outer side wall of the frame.

The angle at which the inclined surfaces 13, 14 are disposed with respect to the vertical section 12, is approximately 10°, as indicated in Fig. 2.

On the other hand, the side of the stock constituting the outer side of the frame of the die 11 is formed with three arcuate sections, the intermediate arcuate section 15 being curved inwardly toward the inside wall of the frame, and the other two outside arcuate sections 16, 17 being curved reversely with respect to said intermediate arcuate section 15. The arcuate sections 16, 17 extend in opposite directions from the ends of the intermediate arcuate section 15 towards the angularly disposed inner wall sections 13, 14, respectively. The construction is such that the intermediate arcuate section 15 constitutes a channel which is co-extensive with the frame of the die 11, and has a height equal approximately to one-third of the height of the die.

The pairs of angularly disposed or tapered walls formed by the surfaces 13, 16 and 14, 17, respectively, provide edges along the top and bottom of the frame of the die 11, which edges are adapted to be ground in well known manner to provide sharp cutting edges, as indicated at 30 18, Fig. 1.

In Figs. 2 and 3, the cutting edges are not shown ground, since these views represent enlarged cross sections of the die stock. However, the cutting edges are indicated by broken lines.

35 As shown in Fig. 2, in order that the die 11 will have great stability while in use, the die stock is so formed as to provide a thickened structure at the portions of the die requiring reinforcement. However, in order to reduce the 40 weight of the material as much as possible and at the same time provide a structure which will be rigid and which will retain its shape under the most severe conditions, it has been found by actual practice, that the intermediate 45 arcuate section 15 can be formed with a radius of curvature not exceeding approximately twice the maximum thickness of the die stock.

Thus, as shown in Fig. 2, if the maximum thickness of the die stock is approximately one-eighth of an inch, the radius of curvature of the 50 arcuate intermediate section 15, may be approximately one-quarter of an inch.

Also the length of the arcs forming the three 55 arcuate sections 15, 16 and 17, should be such that the three arcuate sections constituting the outside peripheral wall of the die, are approximately of equal heights.

These arcuate sections can be so constructed that the radius of curvature of the arcuate sections 60 16 and 17 are approximately six times the length of the radius of curvature of the intermediate arcuate section 15. In this way a cutting edge will be provided by which the material will be cut cleanly and the die can be easily 65 removed from the severed material at the completion of the cutting action.

It will be noted that the contour of the die stock in cross section thus provides material from which the cutting edges 18 can be readily 70 formed by grinding both the outside and inside peripheral surfaces of the frame. Also the body of metal on opposite sides of the channel 15 is considerably heavier than at the central body portion and this assures adequate strength for the cutting edges. The straightening of the die 75

is more readily accomplished with this relatively thinner central body as compared to the former constructions of dies.

The reduced section or channel 15 is not only highly advantageous in making straightening 5 easier, but in use, it permits the operator to grasp the die in order to transfer the same from one material to another material.

The body portion constructed in the above manner becomes a definite limit to any tendency of fatigue cracks to spread. It also facilitates accurate joining of the edges of the die during the welding step.

A modified form of clicking die 21 of the single edge type is shown in Fig. 3, and this has 15 the same vertical plane peripheral surface 22 on the inside and an inclined plane peripheral surface 23 which extends downwardly from the lower portion of the vertical surface 22 towards 20 the cutting edge 24.

The outside of the die 21 has an intermediate channel formed by the arcuate peripheral groove 25.

Extending from the upper edge of the channel 25 is a vertically disposed plane surface 26 25 which is disposed in parallel relationship with respect to the inner peripheral wall 22.

Extending from the lower edge of the channel 25 is a concaved surface 27 which is so disposed as to intersect the bottom of the inner inclined plane peripheral surface 23 so as to form the lower cutting edge 24, which edge is adapted to be ground in well known manner to provide a sharp cutting edge, as indicated by the broken 35 lines in Fig. 3.

In the single edge form of die, shown in Fig. 3, the radius of curvature of the arcuate surface 25 is the same as the length of the radius of the arcuate surface 15. On the other hand, the radius of curvature of the surface 27 is approximately ten and one-half times the radius of curvature of the channel 25. This provides a gradually tapered body for the die leading from the thickest part of the die towards the cutting edge 24.

Opposite to the cutting edge portion of the die there is a blunt edge 28. However, the die has the same advantages of the double edged die shown in Figs. 1 and 2, and can be used in the same clicking presses.

While there is shown herein preferred forms of embodiment of the present invention, it is to be understood that other modifications may be made thereto and I, therefore, desire a broad interpretation of my invention within the scope 55 and spirit of the disclosure herein and of the claims appended hereinafter.

Having thus described my invention, what I claim is:

1. A clicker die of the class described comprising a continuous strip of steel bent into curves and angles of the desired contour and having its ends connected to form a closed frame, an edge of said strip being beveled on both sides to form a cutting edge, a single channel formed longitudinally in the exterior side of the frame, said channel being disposed intermediate to the opposite longitudinal edges of the frame and having a convex surface the radius of which is approximately twice the maximum thickness of the wall 70 of the frame.

2. A clicker die of the class described comprising a continuous strip of steel bent into curves and angles of the desired contour and having its ends connected to form a closed frame, an edge 75

of said strip being beveled on both sides to form a cutting edge, a single channel formed longitudinally in the exterior side of the frame, said channel being disposed equidistant with respect to the opposite longitudinal edges of the frame and having a height equal approximately to one-third of the height of the die.

3. A clicker die of the class described comprising a continuous strip of steel bent into curves and angles of the desired contour and having its ends connected to form a closed frame, the strip of steel comprising said die in cross section having an edge beveled on both sides to form a cutting edge, the beveled portion on the wall constituting the inside of the frame being inclined at an angle of approximately 10 degrees with respect to the vertical center line of said frame and the beveled portion on the outer wall of the frame being arcuate in form, the curvature of said arcuate portion being substantially greater than the height of the frame.

4. A clicker die of the class described comprising a continuous strip of steel bent into curves and angles of the desired contour and having its ends connected to form a closed frame, the strip of steel comprising said die in cross section having three angularly disposed flat peripheral sections on the wall constituting the inside of said frame, the intermediate section of said three sec-

tions being substantially vertically disposed and the other two sections being disposed at an angle to said vertical section and being inclined outwardly towards the outer side wall of said frame, the outer side wall of the frame comprising three arcuate peripheral sections, the intermediate arcuate section being curved inwardly towards the inside wall of the frame, and the other two outside arcuate sections being curved reversely with respect to said intermediate arcuate section and extending in opposite directions from the ends of the intermediate section towards said angularly disposed inner wall sections, whereby to provide cutting edges respectively along the top and bottom of said frame.

5. A clicker die comprising a continuous integral wall, thinner in its middle and presenting inwardly an intermediate substantially vertically disposed peripheral plane surface and upper and lower peripheral plane surfaces angularly disposed with respect to said intermediate surface and inclined outwardly therefrom, and presenting outwardly an intermediate convexed unbroken peripheral surface and upper and lower concaved peripheral surfaces extending from said convexed surface and joined at their upper and lower edges by the edges of said inner inclined plane surfaces, respectively.

FRANCIS J. DEDRICK.
